SOUND RECORDING OSCILLOSCOPE

Harold Leonard Coughlan, Dunedin, New Zealand

Application March 30, 1935, Serial No. 13,986
In New Zealand April 6, 1934

16 Claims. (Cl. 171—95)

This invention relates to sound recording oscilloscopes and more particularly to the production of what are termed sound films or "talkie" films for use with cinematograph production wherein the pictorial action is produced with accompanying sound which occurs with or is co-ordinated with the pictorial representation.

In sound motion picture practice it is customary to produce a cinematograph film record on which there is a series of pictorial representations and at the same time to produce a record of accompanying sound, the sound record being commonly in the form of a continuous record along the side of the film i. e. by the side of the pictures. The sound record may be of any known type, for example it may be the variable density type, or the variable contour (width) type, or a combination of both types. In some cases the sound record is made upon a film or other recording medium separate from the picture film; and in such latter case of course, the sound reproduction must be accurately co-ordinated with the picture film projection so that an observer or audience will receive the impression of simultaneous reproduction of scenes in the picture and the proper accompanying sound.

Further, in sound motion picture production and recording of sound of variable density type or variable contour (or width) type, recording means such as oscilloscopes or the like have been promoted and used to deal with sound-frequency electric currents passed to and through such means from a microphone, along with its associated apparatus.

It is an object of the present invention to provide apparatus for the said recording of sound motion picture films by a high-frequency oscilloscope or the like wherein sound is recorded or traced in either variable contour (width) type or variable density type with preference for the former type, upon the sound track of a motion picture film. To achieve this object reflected light is employed whereby a sound track is produced photographically on a photo-sensitive surface of a suitably arranged material, said photographically produced sound track possessing the major attribute of modern tone-quality performance, while the said (high frequency) oscilloscope is more reliable, rugged and tremendously rigid compared with moving coil type sound recorders made hitherto.

A further object of the present invention is to provide in a reflected light oscilloscope means which will not readily break down, for the tensioned parts will not need to be strained near to their rupture point (as in previous devices) in order to stop spurious vibrations to the detriment of the primary function of the device.

With these objects in view the present invention provides an improved oscilloscope or the like

having means creating a magnetic field, a strip or ribbon of non-magnetic metal supporting a light reflector held in said field and wherein said strip or ribbon is constrained along the edge at least on one side, so that a hinge is formed near where the strip or ribbon is constrained as aforesaid.

The invention will now be further described with reference to the accompanying drawings in which:

Figure 1 is a front elevation of the improved oscilloscope with the casing partly cut away to show the interior.

Figure 2 is a plan of Figure 1 with the cover and its terminals removed.

Figure 3 is an enlarged cross section of the pole face plates and the strip or ribbon through line 3—3 in Figure 1, and,

Figure 4 is an enlarged front elevation of that portion of the strip or ribbon which passes through the gap formed by the pole face plates, and

Figure 5 is a perspective view of the gripper, while

Figure 6 is a view taken on the line 6—6 in Figure 1, without the adjusting mounting.

With reference to the drawings, coils 1, 1a having poles 2, 2a are mounted on a base 3 and may be secured to the latter by bolts 4, 4a and nuts 5, 5a or as illustrated in the drawings insulated spacer bars 6 may be inserted between the poles 2, 2a and the base 3 so as to separate the poles from the base and the whole held together by the bolts 4, 4a and nuts 5, 5a. In this latter connection the lower insulated spacer bar 6 has an extension secured to the base 3 by bolt 6a and nut 6b. By such an arrangement an intense magnetic field can be created by the coils and their plates as hereinafter provided.

The poles 2, 2a are provided with pole face plates 7, 8 which converge towards each other and are adjustable on, and attached to the poles 2, 2a by screws 7a, 8a. The pole face plate 7 has a turned out portion 9 (see Figure 3) and the latter has a notch 9a in the central part of the outer end. The pole face plate 8 has a gripper 10 with a notch 10a in the central part of one end, so that the notches 9a and 10a oppose each other. The other end of the gripper 10 has a sharpened turned in ending 10b preferably accommodated in a groove 11 in the pole face plate 8; and the gripper 10 has holes to take screws 13, 13a which thread into corresponding screw threaded holes in said pole face plate 8 to hold said gripper 10 thereon. Insulating material 12 is placed between the gripper 10 and the pole face plate and preferably also, the gripper 10 is adjustable on the pole face plate 8 by enlarging the holes in the gripper 10 so that the latter is free to move sidewise or slide on the screws 13, 13a.

13a. By such arrangement an intense magnetic field of steady value is produced across a narrow gap 14 thus formed between the ends of the pole face plates 7, 8 in such a manner that all the 5 available flux is passed across and concentrated in such gap.

Also, mounted on the base 3 by means of the spacer bars 6 and between the two poles 2, 2a is a carrier which holds a strip or ribbon of non-magnetic metal, preferably duralumin in the narrow gap 14 formed between the opposing ends of the pole face plates 7, 8 as aforesaid.

The carrier comprises a back plate 15 attached to or an extension of one of the said spacer bars 15, 6, an electric terminal having screws (20a) attaching an electric cable end 21 to the bottom end of the back plate 15, a shoulder 17 mounted by screws 17a above the terminal and below the pole face plates 7, 8, a shoulder 18 mounted on 20 the back of plate 15 above the pole face plates 7, 8 and an adjustable strip or ribbon tensioning means bolted to the upper end of the back plate 15.

The electric cable end 21 secured to the bottom 25 end of the back plate 15 has a strap of insulating material 16a and a bar or plate 20 caught under the screws 20a, and the electric cable end 21 of electric cable 21a is held between said insulating material 16a and said bar or plate 20. Also the 30 bottom end of the strip or ribbon 23 is held between the ending 21 and said bar or plate 20.

The shoulder 17 mounted by screws 17a above the terminal 16 has a rounded protuberance 22 over which the strap of insulating material 16a 35 is drawn and held on the shoulder 17 by the said screws 17a so that preferably said insulating material 16a covers the whole of the outer surface of the shoulder 17. The outer face of the shoulder 17 stands out from the back plate 15 until it is 40 flush with or in the same vertical plane as the outer surface of the pole face plate 8.

The shoulder 18 mounted above the pole face plates 7, 8 has an outer surface 18a flush with and in the same vertical plane as the outer surface 45 of the pole face plate 8 and therefore is also in the same plane as the outer face of the shoulder 17. Further the shoulder 18 has a cut away surface 18b in which near the sides are screws 24, 25 threaded therein. Caught under screw 24 is a slotted washer 26 having an out-turned lug 27 by which the strip or ribbon 23 can be guided as hereinafter described. The top end portion of strip or ribbon 23 is caught under the slotted washer 25a by the screw 25.

55 The adjustable strip or ribbon tensioning means bolted to the upper end of the back plate 15 comprises two posts 28, 29 mounted on a segment 30 and joined by a bar 30a, and said posts and bar support a bridge 31 having a hole 32; said 60 parts 28, 29, 30 and 31 form a recess in which is a slide 34 terminating at its lower end in a strip or ribbon carrier shackle 35 and at its upper end in a threaded bolt 36 which is movable through the hole 32 against a spring 37 under compression 65 between the top of the bridge 31 and a collar 38 which latter is held upon the bolt 36 by a nut 39.

The strip or ribbon 23 caught at its lower end as aforesaid, is drawn over the insulating material 16a, through the gap 14 between the ends 70 of the pole face plates 7, 8 around the outside of the lug 27, passed through the carrier shackle 35 to the screw 25 where the top end portion is secured as previously set forth. It will be appreciated from the foregoing that with a strip or 75 ribbon mounted as aforesaid, adjustment of the

lug 27 by movement of the slotted washer 26 will vary the guidance and the position of the strip or ribbon 23 through the gap 14 between the ends of the pole face plates 7, 8; and that the strip or ribbon 23 can be tensioned by screwing the nut 39 upon the bolt 36 and against the collar 38 and the spring 37 whereby the compression of the latter draws the carrier shackle 35 up, which action tensions the strip or ribbon 23 between its holding means comprising the bar or 10 plate 20 and the cable ending 21 at the bottom, and the screw 25 at the top.

It is an essential part of this invention that the strip or ribbon 23 is held or constrained particularly along one edge while the other or opposite 15 edge is free. With such object in view the gripper 10 is provided as a means for carrying the same into effect; but it will be appreciated that other means could be usefully employed for this purpose, and the invention is not confined to the 20 particular means herein set forth. In effecting this purpose the edge 23a of a strip or ribbon 23 is constrained between the gripper 10 and the pole face plate 8 by screws 13, 13a and such constraining is carried out between insulated surfaces by insulating material 50 attached to the surface of the pole face plate 8 and by insulating material 12 attached to the inner surface of the gripper 10. Further, the edge 23a of the strip or ribbon 23 may have notches or scallops 23b 30 and preferably only the parts or portions 23c of the strip or ribbon 23 between said notches or scallops 23b are caught by the gripper between insulating materials 50 and 12 as aforesaid, so that flexibility in the nature of a hinge is added to 35 the strip or ribbon 23 when and where it is constrained. The strip or ribbon 23 is also provided with a light reflecting surface 40 which is affixed to the strip or ribbon 23 so that when the latter is tensioned as aforesaid, said reflecting surface 40 40 registers with the notches 9a and 10a.

The back plate 15 has an electric terminal 41a which is preferably an earthing terminal for cable 41 so that electric current or impulses either continuous or alternating can pass from the terminal 45 16 through the strip or ribbon 23, and to the said earthing terminal 41a.

The coils 1, 1a are provided with electric cable leads 42 and 42a respectively and through which leads, the said coils are electrically energized in 50 the usual manner well known in the art.

The base 3 is fastened to the inside bottom of a container 43 in such position that the strip or ribbon 23 is immediately behind a lens 44 held at the correct angle of focus in the side of the container 43. Attached underneath the bottom of the container 43 is an adjustable means for adjusting a beam of light reflected from the reflecting surface 40 when such beam is cast through the lens 44, said adjustable means being well 60 known in connection with oscilloscopes.

Preferably sufficient oil is placed in the container 43 so that the parts mounted on the base 3 are submerged within the clear oil bath to reduce 65 the natural vibration period of the ribbon-reflector assembly which in a correctly adjusted unit will occur at an extremely high frequency.

A cover 45 which fits upon the top of the container 43 has electrically insulated terminal buttons 46, 47, 48 and 49 to which are attached cable leads 42, 21a, 41 and 42a respectively. The cover is provided with a convenient hole 19 immediately above the nut 39 so that the latter can be turned 70 for tensioning purposes as hereinbefore described; 75

and said hole is provided with a closure or cap (not shown).

In operation, light from a steady source preferably one of high intensity and focused by means of a suitable lens system (well known in the art) is directed through the lens 44 upon the reflecting surface 40 from where the reflected light is re-imaged at the correct position upon a light sensitive film or photographic negative. Continuous or alternating current, passing through the edgewise constrained strip or ribbon 23 will deflect said image to a degree dependent upon the value of the applied E. M. F. and frequency and the variation in the deflection of the image is optically recorded by well known suitable photographic means.

What I do claim and desire to obtain by Letters Patent of the United States of America is:—

1. In an instrument of the oscilloscope type, means for producing a magnetic field, a vibrating light reflecting means arranged in said field, means for tensioning said light reflecting means above and below said field producing means, and fixed means applied along one edge of said light reflecting means to constrain the movement thereof.

2. In an instrument of the oscilloscope type, a magnetic element for producing a magnetic field, a vibrating light reflecting means arranged in said field, means for tensioning said light reflecting means above and below said magnetic element, fixed means applied edgewise of said light reflecting means to constrain the movement thereof, said constraining means being arranged parallel 35 to the pole faces of the magnetic element and being applied along one side of the light reflecting means the other side of the light reflecting means being free.

3. In an instrument of the oscilloscope type, means for producing a magnetic field, light reflecting means arranged in said field, means applied along one edge of said light reflecting means to constrain the movement thereof, and upper and lower means disposed above and below said magnetic field for guiding said light reflecting means, said constraining means being applied to said light reflecting means throughout its length within said magnetic field.

4. In an instrument as claimed in claim 3, an electric terminal, means conductively associated with said terminal for securing one end of said light reflecting means and means for longitudinally tensioning the last mentioned means.

5. In an instrument as claimed in claim 3, an electric terminal, means conductively associated with said terminal for securing one end of said light reflecting means, said securing means being below the lower guiding means, and means for longitudinally tensioning the light reflecting means disposed above the upper guiding means.

6. In an instrument as claimed in claim 3, an electric terminal, means conductively associated with said terminal for securing one end of said light reflecting means, said securing means including, a bar and insulating means, said bar being disposed on said light reflecting means, said terminal including an electric cable, the end of which is disposed beneath said bar and light reflecting means, and said insulating means being 65 disposed beneath said cable end and means for securing said bar to said light reflecting means.

7. An instrument as claimed in claim 3, wherein in said lower guiding means includes a shoulder the lower outer edge of which is rounded, and 70 insulating means covering said shoulder.

8. An instrument as claimed in claim 3, wherein in said lower guiding means includes a shoulder, the outer surface of said shoulder being in the same vertical plane as said constraining means.

9. An instrument as claimed in claim 3, wherein in said upper guiding means includes a shoulder, the outer surface of said shoulder being in the same vertical plane as said constraining means.

10. In an instrument as claimed in claim 3, two screw bolts fastened to said upper guiding means, slotted washers engaging said screw bolts, one of said washers being provided with an upturned lug for guiding the light reflecting means, the other screw bolt being adapted to secure the upper end of said light reflecting means.

11. In an instrument as claimed in claim 3, means for longitudinally tensioning said light reflecting means, said means comprising a segment, posts in the segment, a bar joining the posts, a bridge provided with a hole supported by said 20 posts and bar, said segment, posts and bridge forming a recess, a slide disposed in said recess, a carrier shackle for the light reflecting means at the lower end of the slide, and a threaded bolt at the upper end of the slide, a collar fixed to said bolt, a spring under compression mounted on said bolt between said bridge and collar, said bolt being movable through said hole against the action of the spring.

12. An instrument as claimed in claim 1, 30 wherein said means for producing a magnetic field comprises coils, pole pieces mounted on a base and passing through said coils, adjustable pole face plates attached to the ends of said pole pieces and cables leading to said coils.

13. An instrument as claimed in claim 2, wherein in the means for producing a magnetic field include pole face plates turned inwardly to form a narrow gap through which said light reflecting means can pass, and a gripper member fixed to one of said plates for securing one edge of said light reflecting means onto the face of the said plate.

14. An instrument as claimed in claim 2, wherein in the means for producing a magnetic field include pole face plates turned inwardly to form a narrow gap through which said light reflecting means can pass, a gripper member fixed to one of said plates for securing one edge of said light reflecting means onto the face of the said plate, and insulating material disposed between the gripper member and the light reflecting means and between the pole face plate and light reflecting means.

15. An instrument as claimed in claim 2, wherein in the means for producing a magnetic field include pole face plates turned inwardly to form a narrow gap through which said light reflecting means can pass, a gripper member fixed to one of 55 said plates for securing one edge of said light reflecting means onto the face of the said plate, and insulating material disposed between the gripper member and the light reflecting means and between the pole face plate and light reflecting means, said pole face plate being provided with a groove and said gripper having a turned-in end to associate therewith.

16. An instrument as claimed in claim 1, wherein in said light reflecting means include a metallic strip and a reflector carried thereby, said strip having a scalloped edge, said constraining means coacting with said scalloped edge.
